COMBINATION SUPPORTING STAND AND CON- TROL PANEL FOR A BACK HOE

John L. French, Moline, and Albert J. Van Auwelaer,
East Moline, Ill., assignors to Deere & Company,
Moline, Ill., a corporation of Delaware

Filed Apr. 15, 1959, Ser. No. 55,527

Term of patent 14 years

(Cl. D14—3)

FIG. 1

FIG. 2

FIG. 3

Fig. 1 is a perspective view showing the rear and right side of a combination supporting stand and control panel for a back hoe embodying our design.

Fig. 2 is a perspective view showing the rear and left side of the supporting stand embodying our design.

Fig. 3 is a perspective view showing the front side of the supporting stand embodying our design.

The depiction of the back hoe and tractor in phantom is for illustrative purposes only.

The back hoe and fragmentary portions of the tractor shown in broken lines are included for illustrative purposes only.

What we claim is:

The ornamental design for a combination supporting stand and control panel for a back hoe, substantially as shown and described.
